DESIGN FOR A TRAFFIC MARKER

Carl A. Glock, Lynwood, Calif.

Application August 13, 1938, Serial No. 79,301

Term of patent 7 years

To all whom it may concern:

Be it known that I, Carl A. Glock, a citizen of the United States, residing at Lynwood, in the county of Los Angeles and State of California, have invented a new, original, and ornamental Design for a Traffic Marker, of which the following is a specification, reference being had to the accompanying drawing, forming a part thereof.

Fig. 1 of the drawing is a perspective view of a traffic marker embodying my new design; and Fig. 2 is an end elevational view of the traffic marker shown in Fig. 1.

I claim:

The ornamental design for a traffic marker, as shown.

CARL A. GLOCK.
